(57) **CLAIM**

The ornamental design for a nozzle for blower, as shown and described.

DESCRIPTION

FIG. 1 is a front view of a nozzle for blower of the present invention.

FIG. 2 is a rear view thereof.

FIG. 3 is a top plan view thereof.

FIG. 4 is a bottom plan view thereof.

FIG. 5 is a right side view thereof.

FIG. 6 is a left side view thereof.

FIG. 7 is a perspective view seen from top, front and left side thereof.

FIG. 8 is a perspective view seen from bottom, rear and right side thereof.

FIG. 9 is an enlarged view of FIG. 5.

FIG. 10 is a cross-sectional view indicated by the arrows 10-10 of FIG. 5; and,

FIG. 11 is a view showing the nozzle for blower in use, wherein a blower and a grip are attached to the nozzle for blower.

The broken lines shown in FIG. 11 depict portions and environment of the article that form no part of the claimed design.

1 Claim, 11 Drawing Sheets
